CLAIM

The ornamental design for a display stand, as shown and described.

DESCRIPTION

FIG. 1 is a perspective view of a display stand showing our new Design in accordance with a first variant of said Design; FIG. 2 is a front view of the display stand shown in FIG. 1; FIG. 3 is a rear view of the display stand shown in FIG. 1; FIG. 4 is a left-side view of the display stand shown in FIG. 1;

FIG. 5 is a right-side view of the display stand shown in FIG. 1;

FIG. 6 is a top plan view of the display stand shown in FIG. 1;

FIG. 7 is a bottom plan view of the display stand shown in FIG. 1;

FIG. 8 is a further perspective view of the display stand shown in FIG. 1;

FIG. 9 is a perspective view of a display stand showing our new Design in accordance with a second variant of said Design;

FIG. 10 is a front view of the display stand shown in FIG. 9;

FIG. 11 is a rear view of the display stand shown in FIG. 9;

FIG. 12 is a left-side view of the display stand shown in FIG. 9;

FIG. 13 is a right-side view of the display stand shown in FIG. 9;

FIG. 14 is a top plan view of the display stand shown in FIG. 9;

FIG. 15 is a bottom plan view of the display stand shown in FIG. 9; and,

FIG. 16 is a further perspective view of the display stand shown in FIG. 9.

Broken lines shown in the Figures represent portions of the display stand that are unclaimed environment, boundaries, contour lines, fold lines, or a combination thereof only, that form no part of the claimed design. The broken lines consisting of evenly sized dashes depict parts of the display stand that form no part of the claimed design. The broken lines consisting of a long dash, a short dash, and a long dash define the bounds of the claimed design and form no part of the claimed design. All surfaces not shown form no part of the claimed design. The oblique line shading in the Figures shows a transparent surface and not surface ornamentation.
